(57) **CLAIM**

The ornamental design for scribe handle, as shown and described.

DESCRIPTION

FIG. 1 is a perspective view of a scribe handle, showing our new design.

FIG. 2 is a left side view thereof.

FIG. 3 is a top view thereof.

FIG. 4 is right view thereof.

FIG. 5 is a bottom view thereof.

FIG. 6 is a rear view thereof; and,

FIG. 7 is a front view thereof.

The broken-line showing of environmental structures in FIGS. 1, 2, and 4 is for illustrative purposes only and forms no part of the claimed design.
